UNITED STATES PATENT OFFICE

DANIEL TROY HAILS, OF CORAL GABLES, FLORIDA

DESIGN FOR A DISPENSER FOR CONFECTIONS OR SIMILAR ARTICLE

Application filed June 14, 1929. Serial No. 31,684. Term of patent 14 years.

To all whom it may concern:

Be it known that I, DANIEL TROY HAILS, a citizen of the United States, and a resident of the city of Coral Gables, in the county of Dade and State of Florida, have invented a new, original, and ornamental Design for a Dispenser for Confections or Similar Article, of which the following is the specification, reference being had to the accompanying drawing, forming a part hereof.

On the drawing:

Figure 1 illustrates a perspective front view of the dispenser for confections or similar article embodying my invention.

I claim:

The ornamental design for a dispenser for confections or similar article, as shown.

DANIEL TROY HAILS.
